SUCTION CLEANER

Daniel Benson Replogle, Berkeley, Calif., assignor to The Ohio Citizens Trust Company, as trustee, Toledo, Ohio, a corporation of Ohio

Original application August 5, 1936, Serial No. 94,439. Divided and this application July 27, 1937, Serial No. 156,032

6 Claims. (Cl. 15—6)

The invention relates to cleaning apparatus and more particularly to portable electric cleaners of the air-method type which may be selectively employed for floor cleaning purposes or by the use of suitable extension devices may be employed for cleaning walls, draperies or the like.

The present application is a division of my prior application Serial No. 94,439 filed August 5, 1936.

One of the objects of the invention is to provide a floor tool for such apparatus, equipped with a pair of rotatable agitators, namely a brush and a beater, rotating in opposite directions. One of the effects of this arrangement is that the beater tends to move the nap of the carpet or other floor covering in one direction and the brush in the opposite direction while the combined action of the two agitators is to leave the nap standing substantially upright after having been thoroughly cleaned, especially when the brush and beating action is combined with the action of an air stream.

Another object of the invention is to provide means for propelling the cleaner in one direction or the other according as the suction box is tilted in one direction or the other about its end rollers.

A further object is to provide a skirt for the floor tool adapted to at all times engage the surface being cleaned in spite of tilting of the suction box.

Other objects will be apparent from a consideration of the accompanying drawings and the following detailed description, in which are set forth illustrative embodiments of the invention.

In the drawings:

Fig. 1 is a side view of the assembled device, parts being shown in elevation while the bag holder is shown in section for the purpose of disclosing the interior;

Fig. 2 is a fragmentary top plan view of the same portions being broken away for the purpose of illustrating details of construction;

Fig. 3 is a vertical sectional view of the floor tool taken on line 3—3 of Fig. 4;

Fig. 4 is a plan view of the floor tool with the motor dome and motor removed;

Fig. 5 is a side elevation of the floor tool with a surface engaging skirt attached thereto;

Fig. 6 is a perspective view of the skirt shown detached from the floor tool;

Fig. 7 is a detailed sectional view on line 7—7 of Fig. 5 showing the seal interposed between the skirt and the suction box;

Fig. 8 is a fragmentary view, partly in section and partly in elevation, showing a portion of the revolving brush and the mounting of the same in the suction box, the section being taken on the line 8—8 of Fig. 3;

Fig. 9 is a detailed view showing the yielding mounting for the brush shaft;

Fig. 10 is a fragmentary section on line 10—10 of Fig. 5 showing the roller support for the suction box and skirt.

The apparatus comprises several principal elements which will be described in detail. The first of these is a wheeled floor tool A which encloses the power plant and suction producing means in the upper portion thereof, and a suction box or nozzle in the lower portion having agitating means actuated by the power plant. The second principal element is the dust collecting and air filtering device B which is swingingly and detachably connected to the floor tool and is equipped with a rigid suction pipe projecting therefrom which serves the function of a handle grip whereby the wheeled cleaner may be moved to and fro across the floor. The third principal element is a flexible, hollow extension member C, communicating with the filter element B which may either be connected to an outlet pipe leading from the suction box or nozzle or may be detached from said tool and used with or without auxiliary extension devices or tools for cleaning walls, ceilings, furniture or even the floor itself.

Referring to the drawings in detail, the floor tool A houses within its upper portion a suitable power plant or suction producing means which includes a motor 19 and a centrifugal fan 11 driven thereby having blades 11a at its periphery. This arrangement of elements is best shown in Fig. 3. Air is discharged from the fan casing 17 through an outlet 12 shown in Fig. 4 and air is drawn into the fan casing through a centrally discharging intake 13. This intake, as best shown in Figs. 1 and 2, has connected thereto a flexible hose 14 or other equivalent connecting means, as, for example, the swinging elbow joint or a pair of such joints as illustrated in my Patent No. 2,009,435, dated July 30, 1935. The flexible hose 14 is connected at its opposite end to a tank or caddy 15 which houses the dust collecting and air filtering unit. The tank is preferably cylindrical in form and may be of metal, hard fibre, "Bakelite," or other suitable material. The caddy or housing 15 is swingingly connected to the floor tool by any suitable means. As shown in Fig. 2, a pair of bracket arms 16 are connected to the

fan casing 17 and project upwardly and rearwardly therefrom on each side of the air inlet 13 and the hose 14. Corresponding arms 18-18 are carried by a removable cap 20 at the base

5 of the caddy and these are hingedly connected at 19 to the arms 16. The connection 19 is preferably adjustable and may be made sufficiently tight so that the weight of the caddy and dust collecting means housed therein will be supported 10 substantially rigidly, or the joint may be loosened to permit the caddy and handle projecting therefrom to be moved up and down to permit sweeping under furniture or other low objects.

15 The end of the caddy opposite the removable cap 20 is closed by a transparent cover 21 which may be of glass, Celluloid or other suitable material. This cover is shown as having a flange 22

20 covered by a U shaped rubber band 22a serving as buffer and as gasket and may be detachably secured to the caddy proper by any suitable means as, for example, stirrup clamps 23-23. The lower half of the cap or cover is irregular in form and is provided with an eccentric opening 24 in a neck or nipple 25. Over this nipple the mouth portion 25 of a dust collector bag 26 is drawn, such bag being preferably composed of porous paper or the like. The mouth of the bag is detachably secured by suitable means, as for example, by a folded over rubber band 27.

30 Owing to the eccentric mounting of the nipple 25 a space is left in the upper portion of the caddy for a lamp 28 which serves to illuminate the transparent cap and to show the operator the quantity of dust being drawn into the filter.

35 A sustaining outer receptacle or bag 29, of wire, matting, or other coarse mesh netting is mounted within the caddy by the use of a suitable collar which frictionally fits the interior of the caddy or may be secured thereto by suitable fastening means, screws or the like. The collar may be of wood, hard fibre, leather, card board, or other suitable material. The inner paper bag is preferably seamless and is adapted to be withdrawn from the caddy as the cap 21 is removed.

45 The top of the cap 21 is provided with an opening 30 into which is fitted a tubular member 31 which is preferably rigid and is adapted to serve as the handle grip portion whereby the cleaner as a whole may be moved across the floor. The 50 handle may be composed of hard fibre, "Bakelite," metal, or other suitable material and is preferably cemented or otherwise permanently secured to the cap 21 so that the handle serves as a means for withdrawing the cap and inner dust collecting bag from the caddy.

To the upper end of the tube 31 may be connected a flexible hose 32 to which may be secured any suitable cleaning tools, suction nozzles or extension devices. As shown in Fig. 1, the end of the hose 32 is fitted within an outlet pipe 33 of the floor tool nozzle, which nozzle is shown as formed by securing a rectangular box or casing 34 below the fan casing 17 by means of suitable fastening device 35, as illustrated in Figs. 3, 4 and 5. The suction box or casing 34 is fluid-tight and constitutes a true suction nozzle, the interior 36 of which is entirely cut off from the fan chamber 37 within the casing 17.

70 The details of construction of the floor tool A are best shown by reference to Figs. 3, 4 and 5. As illustrated, the fan casing 17 is substantially circular in form with a reduced housing 38 or top constituting the motor dome.

75 The motor shaft 39 is vertical and is provided with upper and lower bearings 40 and 41, respec-

tively. As shown in Fig. 4 the lower bearing 41 is supported by a spider 42 which carries the inlet passage 13 leading to the fan motor. It will be noted that air from the inlet 13 enters the fan centrally, adjacent the lower bearing 41 and serves to cool said bearing. This construction would not be permissible were it not for the fact that the entering air has already been filtered, thus removing dust, lint and particles of string which would otherwise wrap around the 10 motor shaft and interfere with its operation. The fan itself may be of a comparatively large size, say of a diameter of 10 inches or more, and is preferably provided near the periphery with a rather large number of blades 11a, say a dozen 15 or more. Where such a large diameter fan is used, the speed of the motor may be slowed down and the power is absorbed by the greater number of blades giving impulse to the moving air. Within the suction box 26 are preferably mounted 20 a pair of rotatable agitators 43 and 44 which are adapted to be actuated in opposite directions by the motor shaft when a suitable clutch operated by inserting the end of the hose pipe 32 in the outlet 33 is actuated. As shown, the agitator 25 43 is in the form of a beater carrying flexible bearing strips. For driving the agitators belts 45 are wound about a sleeve or pulley 46 surrounding an extension of the motor shaft. This sleeve is provided with a cone clutch member 30 47 adapted to engage a similarly shaped portion 48 of the fan shroud. The clutch member 47 is carried by a spring lever 49 pivoted at 50 and having an upturned resilient portion 51 at the end opposite the pivot. The lever 49 tends to 35 drop by gravity until caught by a bracket 52 carried by the top of the suction box, thereby disengaging the clutch so that the agitators remain inoperative, but when the end of the hose 32 is inserted within the box outlet 33, this end 40 engages the upturned cam portion 51 forcing it through a slot 53 in the outlet pipe, at the same time raising the lever 49 and engaging the clutch members 47 and 48.

The suction box 34 is preferably provided with 45 a skirt 54 which is shown attached to the suction box in Fig. 5 and in Fig. 6 is shown detached and in detail. The skirt conforms in shape to the perimeter of the box but is slightly larger and is yieldingly supported on the box at two 50 points by means of the spring shanks 55 of supporting rollers 56 with which the box is equipped. The rollers are mounted at opposite ends of the box and their shanks extend through slots 57 in upstanding ears 58 located at opposite ends of 55 the skirt and into end pockets 59 in the suction box. The assembly is best illustrated in Figs. 5 and 10. The rollers and supports may be of the type shown in my Patent 1,541,280, dated June 9, 1925, and in my Patent 1,994,868, dated March 19, 1935. Tabs 60 are struck out from the ears 58 in forming the slots 57 and these struck out tabs engage a portion of the roller shanks and serve to space the rollers at proper distances from the skirt.

65 The skirt may be of hard fiber, "Bakelite," or other suitable material that will not mar or soil the floor covering which it is adapted to engage. One side of the skirt is arcuately cut away as at 61 to allow for the outlet pipe 33 of the 70 suction box and groove 62 is pressed out from the interior of the skirt forming a rib 63 on the outside over which a rubber bumper 63a is applied to prevent marring the furniture or other objects with which the tool may contact. Around 75

the inside of the skirt a strip 64 is secured by means of staples 65, said strip having an inwardly projecting sealing edge 64a which is adapted to engage the outside of the suction box casing, as illustrated in Fig. 7, to form a fluid-tight connection. The lower edge of the skirt may be serrated, notched, or grooved on one or more sides or ends as at 66 to permit air to enter to prevent sealing the skirt air-tight upon the floor or other surface.

In Fig. 8 I have shown details of construction of one of the agitators with which the suction box is equipped. As illustrated, it comprises a wooden roller 67 which is actuated by the belt 45. To the roller, bristles or beater elements may be applied, depending upon the type of agitator employed. Through the interior of the roller 67 extends a fixed shaft 68, the ends of which are tapered and squared and are adapted to be engaged in rectangular slots 69 formed in yielding flat springs 70 secured to the ends of the suction box or casing. As shown, the agitator is equipped with suitable end bearings, one of which is illustrated at 71, and end collars 72 held in place by pins 73. The mounting of the other agitator is similar and need not be described.

Operation

The operation of the cleaner apparatus will now be described. The fan motor 10 having been started, dust laden air will be drawn into the dust collector from any suitable tool attached to the end of the hose pipe 32, whether it be from the suction box 34 or from extension tools or the like connected to the hose as illustrated in my Patent 1,533,271, dated August 14, 1925. The quantity of dust in the air entering the air filter will be clearly visible to the operator owing to the presence of the transparent cap illuminated by the lamp 28. The dust, lint, strings or other debris having been separated from the air by the filtering paper bag 26 which is supported by the outer bag 29, clean air is drawn centrally into the fan casing 17 through the inlet 13 cooling the lower bearing 41 of the motor, and is then discharged peripherally through the exhaust outlet 12.

When the suction box 34 is to be utilized for floor cleaning purposes, the end of the hose 32 is fitted into the outlet pipe 33 thereby engaging the turned up end 51 of the spring lever 49 and bringing clutch members 47 and 48 into engagement so that the agitators 43 and 44 will be actuated by the motor 10. Since the beater and brush are belted to rotate in opposite directions there will be no strain on the bearing of the pulley or on the motor shaft. The agitators may revolve at a relatively slow rate owing to the small diameter of the pulley or sleeve 46 to which they are belted. This permits the motor to drive the fan 11 at a sufficient peripheral speed to produce the necessary suction. The large diameter of the fan also makes possible the relatively slow rotation of the agitators.

When the cleaner is used upon a carpet with a deep nap, the beater tends to brush the nap in one direction and the brush to move it in the opposite direction. The combined action of the two is to leave the nap standing erect after the dust has been thoroughly cleaned therefrom.

By reason of the yielding connection between the skirt or floor engaging member 54 and the casing of the suction box, it is possible to tilt the floor tool slightly forwardly or rearwardly about the centrally mounted roller supports by simply

raising or lowering the handle 31. While the main portion of the floor tool is tilted the mouth of the skirt, or surface engaging member 54, remains substantially flush with the surface being cleaned, as illustrated in Fig. 5. When the tool is tilted rearwardly by lowering the handle, the agitator 43 will be brought into frictional contact with the surface being cleaned and consequently will tend to move the apparatus forwardly, thus relieving the operator in whole or in part of the labor of pushing the cleaner. On the other hand, when the handle is raised, the front agitator 44 will tend to move the apparatus in the opposite direction.

When a sufficient amount of dust has been collected from the filtering device, which can be determined by inspection through the transparent top of the cleaner, the cover may be withdrawn through the agency of the handle 31, the cap 21 carrying with it the inner paper bag 26 which is then separated from the cap by removing the rubber band 27 whereupon the paper bag and contents may be thrown away, burned or otherwise destroyed and a fresh bag attached to the cap and replaced in the caddy.

The amount of dust remaining on the surface being cleaned may be determined by the operator by simply glancing at the transparent cap during the cleaning operation and if the air being drawn in is relatively clear, it will be apparent that the surface has been adequately cleaned.

The invention has been described in detail for the purpose of illustration, but it will be obvious that variations and modifications may be resorted to without departing from the spirit of the invention.

I claim:

1. A suction cleaner having a floor tool including a suction nozzle, means for yieldingly and tiltingly supporting said suction nozzle in a position normally slightly elevated above the floor, comprising a single pair of rollers mounted on spring supports at opposite ends of a longitudinal axis passing through the nozzle, a pair of oppositely rotating agitators mounted on axes parallel to the common axis of said end rollers, one agitator being in front of and the other in rear of said roller axis, and a surface sealing skirt yieldingly carried by the shanks of said end rollers.

2. In a suction cleaner in combination with a suction box having a pair of oppositely located end pockets, end rollers carried by spring supports maintained in said pockets, and a surface engaging skirt surrounding said suction box and yieldingly supported by said roller supports.

3. A suction cleaner as set forth in claim 2, wherein the skirt is spaced slightly from the suction box and sealing means is interposed between the two.

4. A floor tool for suction cleaners, comprising an open mouthed nozzle casing, a pair of supporting end rollers having their common axis passing through the longitudinal center of the casing, and serving to support the casing above the floor, while permitting the same to be tilted forwardly or rearwardly about said rollers as fulcrums, roller shanks extending beyond the nozzle casing, and a sealing skirt supported on said shanks and extending completely around the casing, and projecting below the same into effective contact with the floor or other surface.

5. In a suction cleaner, in combination with a suction nozzle a pair of spring roller supports extending laterally in opposite directions from said nozzle, rollers mounted on said supports,

and a surface engaging skirt surrounding said nozzle and yieldingly supported by said roller supports.

6. In combination with a suction nozzle, a surface engaging sealing skirt fitting the mouth of the nozzle but separate therefrom, and means resiliently connecting the skirt and nozzle and

normally urging the skirt downwardly and the nozzle upwardly, said means comprising roller shanks and supplementing spring elements therefor supported at the ends of the nozzle, and rollers mounted on said shanks.

DANIEL BENSON REPLOGLE.
